US00D813265S

(12) **United States Design Patent** (10) Patent No.: **US D813,265 S**
(45) Date of Patent: **** Mar. 20, 2018**

(54) **DISPLAY SCREEN OR PORTION THEREOF WITH GRAPHICAL USER INTERFACE**

(71) Applicant: **Smule, Inc.**, San Francisco, CA (US)

(72) Inventors: **Benjamin Hersh**, San Francisco, CA (US); **John Shimmin**, San Francisco, CA (US); **Jeannie Yang**, San Francisco, CA (US); **Perry R. Cook**, Jacksonville, OR (US)

(73) Assignee: **Smule, Inc.**, San Francisco, CA (US)

(**) Term: **15 Years**

(21) Appl. No.: **29/566,269**

(22) Filed: **May 27, 2016**

Related U.S. Application Data

(63) Continuation-in-part of application No. 14/879,075, filed on Oct. 8, 2015, now abandoned.

(51) **LOC (11) Cl.** **14-04**

(52) **U.S. Cl.**

USPC **D14/488**
